ATTORNEY.

UNITED STATES PATENT OFFICE.

CHARLES EDGERTON, OF PHILADELPHIA, PENNSYLVANIA.

STEAM-HEATING APPARATUS.

SPECIFICATION forming part of Letters Patent No. 445,396, dated January 27, 1891.

Application filed January 7, 1890. Serial No. 336,123. (No model.)

To all whom it may concern:

Be it known that I, CHARLES EDGERTON, a citizen of the United States, residing in the city and county of Philadelphia, State of Pennsylvania, have invented a new and useful Improvement in Steam-Heating Apparatus, which improvement is fully set forth in the following specification and accompanying drawings.

10 My invention consists of means whereby the live steam of a steam-heating apparatus is employed as a motor for causing the return of the water of condensation to the boiler or generator.

15 Figure 1 represents a side elevation of steam-heating apparatus embodying my invention. Fig. 2 represents a section on line *xx*, Fig. 3, of motor constituting part of my invention.

20 Fig. 3 represents a section on line *yy*, Fig. 2. Similar letters of reference indicate corresponding parts in the several figures.

Referring to the drawings, A designates radiators, B the pipes which convey steam from the boiler or generator C to said radiators, and D designates the pipes which lead from the radiators for conveying the water of condensation therefrom, which parts, excepting the features of my invention applied thereto, are as usual in steam-heating apparatus.

25 E designates an engine, which is connected with the generator C by a pipe F and has the supply end of the pipes B connected therewith.

30 G designates a pump, which has connected with it the discharge end of the pipes D and also a pipe H, which is in communication with the water-space of the generator. The said

engine and pump consist of two independent casings E' and G' and a shaft G², common to said engine and pump, extending through said casings. Blades J are connected to the shaft in the engine-casing E', and blades J' are also attached to said shaft in the casing G' of the pump G. Live steam from the generator enters the engine E, and, striking the blades J' thereof, rotates the shaft G². The steam passes out from the said engine through the pipe B to the radiators A. The rotation of the shaft G² by the live steam, as stated, imparts movement to the blades J' of the pump G, and the water of condensation collected by pipes D is sucked up into and through the said pump and forced out through the pipe H into the boiler of the generator, where it is again converted into steam.

Having thus described my invention, what I claim as new, and desire to secure by Letters Patent, is—

In a steam-heating apparatus, a steam-generator, a radiator, a live-steam-conveying pipe, and a pipe for the return of exhaust or condensed steam, combined with an engine or motor, a pump, the said engine or motor and pump having a shaft common to both and respectively connected to the live and exhaust steam pipes, and a pipe connected to said pump and generator, whereby the water of condensation or exhaust is forced back to the boiler of said generator, substantially as described.

CHARLES EDGERTON.
